Patented Dec. 22, 1959

186,906

COMBINED MARINE LIGHT AND FLAGSTAFF

Donald J. Behnk and Glenn W. Monigle, Pittsburgh, Pa.,
assignors to Attwood Brass Works, Inc., Grand Rapids,
Mich., a corporation of Michigan

Application May 14, 1958, Serial No. 50,880

Term of patent 14 years

(Cl. D48—32)

Fig. 1 is a perspective view of a combined marine light and flagstaff showing our new design.

Fig. 2 is a side elevational view thereof.

Fig. 3 is a rear elevational view thereof.

Fig. 4 is a top plan view thereof.

We claim:

The ornamental design for a combined marine light and flagstaff, substantially as shown.
